UNITED STATES PATENT OFFICE.

FREDERIC HARRINGTON AND BENJAMIN L. CARTER, OF CLEVELAND, OHIO.

UMBRELLA-EXHIBITOR.

SPECIFICATION forming part of Letters Patent No. 404,480, dated June 4, 1889.

Application filed October 11, 1888. Serial No. 287,871. (No model.)

To all whom it may concern:

Be it known that we, FREDERIC HARRINGTON and BENJAMIN L. CARTER, citizens of the United States, residing at Cleveland, in the county of Cuyahoga and State of Ohio, have invented certain new and useful Improvements in Umbrella-Exhibitors; and we do hereby declare that the following is a full, clear, and exact description of the invention, 10 which will enable others skilled in the art to which it appertains to make and use the same.

Our invention relates to umbrella-exhibitors, and the object is to provide means whereby umbrellas may be exposed for exhibition 15 in such a manner that each and all can be readily brought into convenient view before a purchaser and inspected and compared, and where the relative size, quality, and price may be ascertained without removing the same 20 from their support. Hitherto the only devices having these objects in view have been stands or racks, placed generally upon the floor and where the umbrellas could only be examined by handling them one at a time, thus producing 25 shop-wear, which would detract from their appearance and value, as well as be lacking in that artistic display which frequently is an incentive to purchase. By our arrangement the best possible effect is obtained in the exhibition of the goods, while the goods are preserved from the handling, which in time works 30 serious injury to their sale.

To these ends the invention consists in the construction and arrangement of parts, substantially as shown and described, and particularly pointed out in the claims.

In the accompanying drawings, forming part of this specification, Figure 1 is a perspective view of our exhibitor or support with 40 umbrellas thereon as in use. Fig. 2 is an enlarged side view of a section of one of the endless chains and of the grooved wheels on which the chains are supported. Fig. 3 is a detail of one of the grips by which the body of the 45 umbrella is held in the chain.

In the views here shown we have preferably arranged the exhibitor as suspended from the ceiling over the counter, and to this end we have employed tubular brackets A, screwed 50 through flanges to the ceiling and having hollow elbows a at their bottom, which form bear-

ings for a shaft B. Upon the shaft B are mounted, at suitable distance apart, two wheels C, having grooves c around their periphery. Upon the wheels C are swung two 55 endless chains D, of equal length, and these chains are each provided alternately with grips E and staples F. The chains D are formed with flat links, so that they will ride round on the wheels on the same surface, and 60 the grips and staples are rigidly secured on the face of the chains through their stems e and f, respectively, so that they will stand out at right angles to the flat surface of the chains and hold that relation when all the parts are 65 mounted and at work.

The grips E are made of spring metal of such size as to grasp and hold the umbrella around its larger part near the handle, while the staples F are formed with eyes, into which the 70 top of the umbrella is inserted. The wearing-surface of both holders is smooth, so as not to injure the finest fabric, and by the construction described the greatest facility is afforded for removing and replacing the goods 75 in the exhibitor. These holders are arranged at such distances apart that each umbrella is separately and fully exhibited to view, thus affording the best possible opportunity for striking contrasts and comparisons of merits. 80

Obviously, if preferred, a portable frame may be provided for supporting the exhibitor, and it may be hung in a show-window or placed anywhere that convenience or taste may suggest; nor need the exact details herein shown 85 and described be followed in every particular, the invention being only limited by the broader principles of construction covered by the claims. For example, a single drum with an endless apron might be used instead of the 90 two wheels and two separate chains, and the form of the holders for the umbrellas is susceptible of great variation.

The use of the term "umbrellas" is understood to cover parasols and the like, and the 95 use of the term "wheel" or "wheels" covers such equivalent constructions, as a drum, or the like, above described, which would be practically the same thing.

Having thus described our invention, what 100 we claim as new, and desire to secure by Letters Patent, is—

1. An umbrella-exhibitor consisting in an endless carrier or carriers, and a wheel or wheels on which said carrier or carriers are supported, with holders for the umbrellas on the carrier or carriers, substantially as set forth.

2. In an umbrella-exhibitor, endless chains, one of which has a spring-grip and the other a staple, with an eye for holding the umbrel-

las and wheels on which said chains are hung, substantially as set forth.

In testimony whereof we hereunto set our hands this 9th day of October, 1888.

FREDERIC HARRINGTON.
BENJAMIN L. CARTER.
